UNITED STATES PATENT OFFICE.

FREDERICK H. WEEKS, OF AKRON, OHIO.

DESIGN FOR A JUG.

SPECIFICATION forming part of Design No. 20,988, dated August 11, 1891.

Application filed June 17, 1891. Serial No. 396,640. Term of patent 14 years.

To all whom it may concern:

Be it known that I, FREDERICK H. WEEKS, a citizen of the United States, residing at Akron, in the county of Summit and State of Ohio, have invented and produced a new and original Design for Jugs, of which the following is a specification, reference being had to the accompanying drawings.

Figures 1 and 2 are elevations taken at right angles to each other, the former being a side view; and Fig. 3 is a horizontal section.

The leading feature of my design is that while the jug in the main is or may be approximately spherical it has two flattened sides located opposite each other, each of these sides having an outwardly-projecting rim A, inclosing, respectively, sunken panels B. The jug has a depending rim C, that serves as a supporting-base. The handle D and nozzle E may be of ordinary form. The sunken panels B are usually ornamented in relief by representations of, for instance, fruit, flowers, vines, leaves, &c., such ornamental work in

the present instance being a quince-branch bearing leaves and fruit. The rim C is shown 25 ornamented with an imitation of repoussé work. There are plain bands G extending from base to nozzle, the base or lower leg of the handle being planted on one of these bands. There are also a series of lateral 30 bands H, usually ornamented, in the present instance ornamented with a rude representation of a reptile's head and neck, as at h. Between bands H is raised work representing scales, as at I. 35

What I claim is—

The design for jugs herein shown and described.

In testimony whereof I sign this specification, in the presence of two witnesses, this 40 23d day of May, 1891.

FREDERICK H. WEEKS.

Witnesses:

A. E. KLING,
HARVEY MUSSER.
